OPERATING ATTACHMENT FOR THE HANDLES OF AB RELEASE VALVES

Sylvester L. Joiner, Sweetwater, Tex.

Application February 8, 1946, Serial No. 646,428

7 Claims. (Cl. 74—479)

1

This invention relates to an operating attachment for the handle of an AB release valve and it is primarily an object of the invention to provide an attachment of this kind which can be conveniently operated to free the release valve from the side of the car immediately adjacent to the triple valve.

It is also an object of the invention to provide an attachment of this kind so constructed and applied to provide means for effectively maintaining the handle of the release valve in its neutral position so as to substantially eliminate any accidental bleeding of the release valve.

It is an additional object of the invention to provide an attachment for the handle of an AB release valve which has articulated connection with the handle and which is suspended in a manner to eliminate liability of any binding portion becoming fouled to cause the valve plunger to stay open with a resultant undesirable leakage or bleeding.

A further object of the invention is to provide an attachment for the handle of an AB release valve which is adapted to be directly grasped by a trainman at one side of the car for opening the valve plunger but which is operated by a release rod from the opposite side of the car.

The invention consists in the details of construction and in the combination and arrangement of the several parts of my improved operating attachment for the handle of an AB release valve whereby certain important advantages are attained, as will be hereinafter more fully set forth.

In order that my invention may be better understood, I will now proceed to describe the same with reference to the accompanying drawings, wherein:

Figure 1 is a fragmentary view partly in section and partly in elevation illustrating an attachment constructed in accordance with an embodiment of my invention in applied position, the associated parts of the release valve and the release rod being shown in fragment;

Figure 2 is a sectional view taken substantially on the line 2—2 of Figure 1, looking in the direction of the arrow;

Figure 3 is a fragmentary view in outer side elevation illustrating the attachment;

Figure 4 is a view in side elevation of another embodiment of the invention;

Figure 5 is a view in section on the line 5—5 of Figure 4 looking in the direction of the arrow;

Figure 6 is a fragmentary elevational view

2

illustrating a further embodiment of the invention;

Figure 7 is a sectional view taken substantially on the line 7—7 of Figure 6; and

Figure 8 is a fragmentary view partly in section and partly in elevation illustrating a still further embodiment of the invention.

In the embodiment of the invention as illustrated in Figures 1 to 3 of the drawings, H denotes the handle of an AB release valve and which coacts with the plunger P within the valve body B for moving the plunger P into open position upon tilting or rocking movement of the handle H as is well known.

The lower or outer end portion of the handle H is provided with a fork F and operatively engaged with the arms 1 of said fork F and bridging the space therebetween is a pin 2. This pin 2 is freely passed through the ring-like coupler member or connector 3. This member 3 is free for either lateral swinging or revolving movement as an articulated connection is provided which is substantially universal.

This coupler member or connector 3 is provided with the rigid outstanding fork 4 with which is pivotally connected, as at 5, an end portion of a release rod R. This rod R extends to the side of the car remote from the triple valve of which the relief valve forms a part and which triple valve in the modern assembly is placed closely adjacent to one side of the car.

Also freely disposed through the ring-like coupler 3 is a pin 6 carried by and bridging the space between the arms 7 of the fork A at the upper end portion of an elongated hand grasp G.

When it is desired to bleed the release valve, the trainman, if at the same side of the car as the triple valve, is only required to take hold of the hand grasp G and pull the same sufficiently to rock the handle H to move the plunger P into open position, whereas if the trainman should be at the opposite side of the car, he can readily effect the desired opening of the plunger P by pull upon the release valve R.

By making it necessary for the trainman at the triple valve side of the car to directly pull the hand grasp G, there is eliminated the tendency on the part of the trainman to kick the handle H or to strike such handle H with the brake club. Should the trainman kick or strike the hand grasp G, there would be no action upon the handle H due to the free articulated mounting of the hand grasp G through the instrumentality of the coupler or connector 3. It is also true that the trainman cannot open the plunger P by kicking

or striking the outer end of the release rod R on account of the same free articulated connection afforded by the coupler or connector 3.

In the embodiment of the invention as illustrated in Figures 4 and 5, the coupler member or connector comprises a plate 8, herein disclosed as of a quadrant form although I do not wish to be limited in this respect. This plate 8 is provided with the aligned spaced openings 9 and 10, the opening 9 to be considered as the upper opening and the opening 10 as the lower opening.

The upper opening 9 has freely inserted therethrough the pin 11 carried by the fork at the outer or lower end of the handle B for the AB release valve while the lower opening 10 has freely disposed therethrough the pin 12 carried by the fork 14 at one end of the hand grasp 15. The plate 8 at its lower portion is provided with a laterally directed fork 16 which is adapted to be pivotally connected, as at 17, with the inner extremity of a release rod 18.

In this second embodiment of the invention, it is to be noted that the hand grasp 15 and also the release rod 18 have such articulated connection with the handle B to eliminate opening the valve plunger by kicking or striking either the hand grasp 15 or the release rod 18.

In the embodiment of the invention as illustrated in Figures 6 and 7 of the drawings, the coupler member or connector 19 is herein disclosed as substantially semicircular in form and in a plane aligned with its straight edge 20 is provided with the suitably spaced openings 21 and 22. The lower opening 22 provides means for articulated connection with the hand grasp 23 while the upper opening 21 allows the desired pivotal connection with the outer or lower end portion of the handle 24 for the valve plunger.

The member or connector 19 substantially centrally of its straight edge 20 is provided with the outstanding spaced arms 25 between which are received the inner extremity of a release rod 26, said arms 25 and rod 26 being pivotally connected, as at 27. In this third embodiment of the invention, the same beneficial articulation is provided to prevent opening of the plunger of the valve as the result of either kicking or striking.

In the embodiment of the invention as illustrated in Figure 8, the coupler member or connector comprises a body 28 with which is swivelly connected a depending eye member 29 for free articulated connection, as at 30, with one end portion of the hand grasp 31.

The opposite or upper end of the body 28 is provided with an upstanding loop member 32 which provides means for a free articulated connection between the body 28 and the outer or lower end portion of the handle 33 for the plunger of the release valve. The body 28 is provided with a laterally disposed and outwardly directed fork 34 with which is pivotally connected, as at 35, the inner end portion of the release rod 36.

In this last embodiment of the invention, it is believed to be equally apparent that the assembly is one which will substantially eliminate opening of the valve plunger as the result of either a kick or strike.

It is also believed to be obvious that in each of the embodiments of the invention as hereinbefore set forth, the assembly is one whereby the handle for the plunger of the valve will normally be

maintained in a neutral position and which position will not be affected by fouling or sticking of the associated release rod which is operated from the side of the car remote from the triple valve.

From the foregoing description it is thought to be obvious that an operating attachment for the handle of an AB release valve constructed in accordance with my invention is particularly well adapted for use by reason of the convenience and facility with which it may be assembled and operated.

I claim:

1. In combination with the operating handle for the plunger of an AB release valve, a ring-like connector freely engaged with the handle, a release rod, and a pivotal connection between the ring-like connector and the release rod.

2. In combination with the operating handle for the plunger of an AB release valve, a ring-like connector freely engaged with the handle, a release rod, a pivotal connection between the ring-like connector and the release rod, a hand grasp, and means for freely connecting the hand grasp with the ring-like connector.

3. In combination with the handle for the plunger of an AB release valve, a connector comprising a plate, means for freely connecting the plate with the handle, a release rod, means for freely connecting the release rod with the plate, a hand grasp, and an articulated connection between the hand grasp and the plate.

4. In combination with the handle for the plunger of an AB release valve, a connector comprising a body, means for freely engaging the body with the handle, a release rod, an articulated connection between the release rod and body, a hand grasp, and a swiveled articulated connection between the hand grasp and the body.

5. In an AB release valve having a plunger and a handle connected with and depending from the plunger; operating means for the plunger comprising a connector attached to and hanging from the handle, a hand grasp attached to and hanging from the connector substantially directly below said handle, and a release rod attached to and extending laterally from one side of the connector.

6. Operating means for an AB release valve as set forth in claim 5, wherein the attachment of the connector to the handle is pivotal and the attachment between the hand grasp and the connector and between the release rod and the connector is in each case pivotal.

7. Operating means for an AB release valve as stated in claim 5, wherein the attachments between the connector and the handle, hand grasp and release rod are pivotal for turning on parallel axes.

SYLVESTER L. JOINER.
